VELOCIPEDe STEP

William C. Roe, Elyria, Ohio, assignor to The Colson Corporation, Elyria, Ohio, a corporation of Ohio

Application November 3, 1950, Serial No. 12,829

Term of patent 14 years

(Cl. D90—8)

To all whom it may concern:

Be it known that I, William C. Roe, a citizen of the United States, residing at Elyria, in the county of Cuyahoga and State of Ohio, have invented a new, original, and ornamental Design for Velocipede Step, of which the following is a specification, reference being had to the accompanying drawing, forming a part thereof.

Figure 1 is a rear elevation in perspective of the velocipede step embodying my new design;

Figure 2 is a top plan view of the step, and Figure 3 is a side elevational view of the step.

The dotted lines in the drawings are included for illustrative purposes only.

I claim:

The ornamental design for a velocipede step, substantially as shown and described.

WILLIAM C. ROE.
